UNITED STATES PATENT OFFICE

2,535,859

TIMING DEVICE FOR FEEDING ARTICLES
FROM MULTIPLE TO SINGLE ROWS

Robert M. McPherson, San Leandro, Calif., assignor to Continental Can Company, Inc., New York, N. Y., a corporation of New York

Application January 5, 1946, Serial No. 639,481

9 Claims. (Cl. 198—32)

1

This invention relates to a dual timing device, that is, to a mechanism adapted to receive articles from two separate sources or stations and deliver the said articles in timed and spaced relation to a conveyor leading from said mechanism to another single station.

Specifically, the device forming the subject matter of this application is designed for use in cannning factories for delivering filled cans from two filling machines to a single capper and seamer; but it is to be understood that the invention is not to be considered as limited to such specific use as it is adaptable for use in delivering cans or other articles from any two stations or sources to the next station in order, particularly where the mechanism at the station to which the cans are to be delivered is more speedy in operation than that of the mechanisms from which the cans are received. However with this understanding as to the broader use of the invention, the following description will be confined to the delivery of the cans from two filling mechanisms to a can capper, which usually includes a double seamer.

It is well known in the cannning art that said double seaming cappers are much more rapid in operation than the can filling machines, so that one filling machine cannot supply a sufficient number of filled cans to the capper to effectively maintain the latter in operation at full capacity.

It has been proposed to deliver the cans from the filling machines to a single capper, but it is impractical to deliver the lines of cans issuing from the two filling machines directly and simultaneously to a capper, as the cans must be fed to the capper singly and in timed relation. Hence, in carrying out this idea, it is necessary to provide means for receiving the two lines of cans mentioned, and coordinate them so as to deliver single cans in spaced and timed relation to the capper.

Furthermore, it is essential that the cans be taken alternately from the two feed lines in order to avoid congestion in either one line or the other.

The object of the present invention is to provide means for receiving two separate and continuous lines of articles, and for coordinating and delivering the articles in a single line, with the articles in the desired spaced relation.

A further and specific object of the invention is to provide a device of the character mentioned adapted to receive separate lines of cans issuing from a pair of filling machines, and coordinate the cans of the two lines and deliver

them in timed and spaced relation to the feed belt of a capping machine.

A further object of the invention is to provide a device as mentioned which will operate smoothly and gently upon the filled cans as they are received, coordinated and selectively delivered to the capping machine feed conveyor, so as to avoid spilling any appreciable portion of the contents of the filled cans.

A further object of the invention is to provide in a dual timing machine as mentioned, means whereby the device can be adapted and synchronized to various types of machines, either those from which the cans are received or the single machine to which they are to be delivered, or both.

With these and other objects in view as will hereinafter appear, the invention consists generally in a rotary timing spiral, means for feeding articles to said spiral upon opposite sides thereof, and means for maintaining the articles in operative engagement with said spiral and for guiding them into a single line as they leave the end of the spiral.

The invention further consists in a device as above stated in which the feeding means run substantially parallel with the axis of the rotary spiral and on opposite sides thereof, in combination with a single continuous delivery device leading from adjacent the delivery end of the spiral.

The invention further consists in a rotary timing spiral, friction feed conveyor arranged upon opposite sides of the spiral and substantially parallel therewith to feed two lines of cans to and along said timing spiral, and means for moving the feed conveyor at a greater forward speed than the forward advance of the convolutions of the spiral.

The invention further consists in a device as above stated in which the crest of the convolutions of the spiral increases in pitch from the receiving to the delivery end so as to permit speeding up the movement of the cans as they are delivered from the machine thereby avoiding congestion in coordinating the cans from the two sources, and to synchronize the delivery time to the operation time of a capping machine.

The invention further consists in the combination of a timing spiral, feed conveyors and a receiving belt as mentioned, in which the spiral is synchronized to the speed of the feed conveyor so as to initially retard the forward movement of the cans and then gradually permit acceleration of the same so as to deliver the cans to the

2

receiving conveyor without congestion of the cans in the device.

The invention further consists in various details of construction and combination of parts all of which will be fully described hereinafter and particularly pointed out in the claims.

The invention will be more readily understood by reference to the accompanying drawings forming a part of the specification, and in which:

Figure 1 is a plan view of a dual timing machine embodying my invention.

Figure 2 is a side elevation of the device upon an enlarged scale.

Figure 3 is a bottom plan view of the device, illustrating the driving and actuating means.

Figure 4 is a cross-sectional view taken substantially on the line 4—4 of Figures 2 and 3.

Figure 5 is a detail end elevation of the table illustrating the driving means for the timing spiral.

Figure 6 is a detail vertical longitudinal section at the delivery end of the device, taken on the line 6—6 of Figure 1 and illustrated upon a much enlarged scale.

Figure 7 is a detail plan view of a portion of the guide rail assembly.

Figure 8 is a detail sectional view on the line 8—8 of Figures 1 and 7.

The specific embodiment of the invention, as illustrated in the drawings, is designed to receive lines of cans from two filling machines and to deliver the same in a single line to the feed belt of a capping machine. As shown, the device comprises a suitably supported feed table, a timing spiral rotatably mounted on a horizontal axis above the said table, feed conveyors supported on said table and lying parallel to the axis of the spiral and on opposite sides thereof, means for feeding separate lines of cans to said conveyors respectively, means for maintaining the cans on the belts in operative relation with said spiral, a belt at the discharge end of the table and means for synchronously operating the several parts.

Referring to the drawings, 10 indicates the feed table which is provided at the receiving end with a pair of adjustable supports 11 by which it may be leveled and trued with relation to the associated mechanisms above mentioned. The opposite or discharge end of the table is preferably secured to and supported by the frame or other suitable portion 12 of the station or machine to which the cans are to be delivered, such as a capping machine.

Mounted horizontally above the table 10 is a longitudinally disposed spiral 13, the pitch of the convolutions of which increases from the receiving to the delivery end. Also, the diameter of the root 15 of the spiral is substantially uniform for the greater portion of its length and then gradually lessens to a minus value; that is, the root diameter lessens until it intersects and then passes the axis 16 of the spiral, as indicated at 17 in Figure 6 of the drawings. The purpose of this construction will appear hereinafter.

Upon opposite sides of the spiral 13 and parallel therewith are endless conveyors, the upper laps of which travel in longitudinal grooves in the top of the table 10 with their upper faces slightly above the surface of the table to frictionally support and convey the cans fed thereto.

Preferably, there are two such conveyors upon each side of the spiral, a long conveyor chain 18 and a shorter conveyor chain 19. The long chain 18 extends practically the length of the table and is positioned close to the spiral to support one side

of the cans, and the shorter chain 19 is spaced laterally therefrom to support the outer side of the cans. These chains are preferably of the type known as block chains and are supported in the longitudinal grooves 20 on wear plates 21.

The feed chains 18 and 19 are actuated by sprockets 22 fixed to a drive shaft 23 extending transversely of the machine and supported in bearings 24. The shaft 23 is driven from a power shaft 25 parallel thereto and supported in bearings 26.

It is the purpose of this invention to provide means for feeding cans to a capper from two sources such as two filling machines, so that the capper may be maintained in operation at full capacity. It is therefore necessary that the dual timing machine constituting the present invention shall be synchronized with the operation of the capper. To this end the power shaft 25 is driven by a power drive chain which receives its power directly from the capper, said chain also constituting the conveyor for receiving the cans from the feed conveyors and spiral and delivering the same to the capper. The combination drive chain and conveyor which is indicated at 27, engages with a sprocket 28 on the power shaft to actuate the same. The drive shaft 23 and power shaft 25 at one end project outwardly beyond the side of the table 10 and upon the projecting ends of the shafts are sprockets 29 and 30, respectively, connected by a sprocket chain 31. This sprocket gearing is enclosed by a guard or housing 32. The sprockets 29 and 30 may be replaced by sprockets of different sizes so as to accurately time the feed chains 18 and 19 to the delivery chain 27. This is essential for adapting the device to different types of cappers or other machines.

The cans are delivered from the filling or other machines, not illustrated, to the feed chains 18 and 19 by feed disks 33 mounted on vertical shafts 34 supported in bearing sleeves 35 of brackets 36, which brackets project laterally from the sides of the table adjacent the feed end thereof. These disks overhang the table top, which is preferably recessed as at 37 to accommodate them, so that the tops of said disks are in the same plane with the upper faces of the feed chains 18 and 19. The chains 18 are substantially tangential to the periphery of the disks, and the chains 19 extend to approximately the intersection of the same with the said peripheries.

Extending longitudinally of the table is a shaft 38 supported in bearings 39 and geared to the power shaft 25 by bevel gears 40. A transverse shaft 41, mounted in bearings 42 beneath the table, is connected to the shaft 38 by bevel gears 43, and is provided with a sprocket gear 44.

Parallel with the shaft 41, and extending transversely of the table between the vertical shafts 34 of the feed disks, is a shaft 46 having a sprocket 47 adjustably secured thereto as by a set screw 48. A sprocket chain 49 connects the sprockets 44 and 47. Fixed to the ends of the shaft are bevel pinions 50 which mesh with bevel gears 51 fixed to the vertical shafts 34 of the feed disks. Housings 52 are provided for the gearing 50—51.

One end of the shaft 38 extends beyond the end of the table and is provided with a sprocket 52 which is connected by a sprocket chain 53 with a sprocket 54 on the end of the shaft 55 of the rotary spiral 13. The shaft 55 is mounted in bearing blocks 56 and 57 on the top of the table 10. A housing or guard 58 is provided for the sprocket 54 gearing just described.

As hereinbefore described, the feed chains 18 and 19 are engaged and driven by sprockets 22 on the shaft 23 adjacent the delivery end of the machine. The shorter chains 18 at their inner limit of movement extend about idler sprockets 59 mounted on a transverse idler shaft 60, and the lower laps extend beneath idlers 61 on the end of arms 62 adjustably mounted on brackets 63 depending beneath the table 10. The longer chains 18 similarly extend about idlers 64 on shaft 41, the lower laps of said chains passing over idlers 65 on arms 66 adjustably mounted on depending brackets 67 and then under idlers 68 on shaft 46.

Referring particularly to Figure 1 of the drawings, it will be noted that the width of the spiral shaft bearing block 56 is substantially the same as the root diameter of the spiral at the adjacent end thereof; and extending rearwardly and as continuations of the side faces of said block are diverging arms 69 to which are attached outer arcuate can guide rails 70 which are concentric with the disks 33 and adjacent the peripheries thereof. These rails are further supported by brackets 71 secured to and extending upwardly from the top of the table 10. The brackets 71 are each formed of a single strip bent to form a foot 72 which is attached to the table, a vertically extending portion 73, a horizontal top portion 74 sufficiently elevated to clear the tops of the tallest cans, and a depending arm 75. The guide 70 is attached to the portion 73, as at 76, and to the lower end of the arm 75 is secured, as at 77, an inner can guide 78 concentric with the guide 70 and spaced therefrom sufficiently to permit the cans to pass between them as they are received from the filling machines and delivered to the timing spiral and feed chains 18 and 19. In Figure 1, 79 indicates the cans in two lines as received from two filling machines and at the different stages as they pass through the dual timer to the conveyor belt 27 at the delivery end of the machine.

As the cans are deposited on the feed disks 33, which are continuously rotated in the direction of the arrows (see Figure 1), they are carried between the guides 70 and 78 past the arms 69 and bearing block 56 where the inner portions of the bottoms of the cans rest upon the feed chains 18 and the sides of the cans engage the spiral 13. The cans are then moved forwardly by the feed chains, and as they pass beyond the periphery of the disks, the outer portion of the bottoms of the cans rest upon the chains 19.

Adjustable lateral guides are provided for maintaining the cans constantly in engagement with the root 15 of the spiral as they are moved along said spiral by the conveyors 18 and 19. These guides, one on each side of the spiral, are each formed of a plurality of adjustable sections, and comprise upper and lower rails, the inner edges of which are in vertical alignment and approximately equidistant above and below the end of the axis of the spiral 13 so as to gently but firmly hold the cans to prevent jarring or tipping the same. The guide rails on each side of the spiral are alike, so the description of one will suffice for both.

The first section of each of said lateral guides is hingedly mounted and constitutes means for applying yielding pressure to the cans to hold them in engagement with the root of the spiral throughout the portion thereof which is of uniform diameter. This section is illustrated particularly in Figures 1, 7 and 8 of the drawings,

the top rails being omitted in Figure 7 to better illustrate the construction and operation of the section. As shown in said figures, this hinged guide assembly comprises a base adjustably secured to the top of the table 10, the guide hingedly mounted thereon, means for yieldingly pressing said guide inwardly, and adjustable means for limiting the inward movement of the same.

The base of said hinged guide assembly comprises an elongated arm portion 80 having a transversely enlarged forward end 81 provided with transverse slots 82 to receive bolts 83 by which it is adjustably secured in position on the table top. The arm 80 is spaced a short distance above the table top and projects a considerable distance over the adjacent rotary disk 33. The arm 80, adjacent the slotted forward end, is provided with a vertical pivot pin 84 upon which the guide rail section is hingedly mounted.

The hingedly mounted guide rail section per se, comprises a bottom rail portion 85 having a sleeve 86 at its forward end mounted on the pin 84, and an upper rail 87 spaced from the bottom rail by a pair of vertical spacers 88. The inner edges of both rails are straight for the major portion of their length, terminating at the rearward end in an outwardly curved portion 89 contiguous to the end of the arcuate guide 78. Formed on the base arm 80 is an upstanding lug 90 on which is pivotally mounted a cam 91 having an outwardly extending stem 92 on which a weight 93 is adjustably mounted. The cam 91 constantly engages the outer edge of the rail 85, as shown in Figure 8, and yieldably forces the hinged guide inwardly against the cans due to the weight 93.

The curved end 89 of the hinged guide section projects slightly into the path of the cans so that the cans entering between the guide rails 85 and 87 and the arm 69 will force said ends outwardly momentarily, but this outward movement is limited by an adjustable set screw 94 threaded through the lug 90. The limit of movement of the end 89 into the path of the cans is controlled by a set screw 95, threaded through a flange 96 on the arm 80 to engage a forwardly extending lug 97 on the sleeve 86.

As hereinbefore stated, the root diameter of the spiral is substantially uniform for the greater portion of its length and then gradually lessens to a minus value at the delivery end. The hinged guide section above described presents straight guide edges parallel with that portion of the root of the spiral which is of uniform diameter and terminates at the pivotal mounting substantially opposite where the root diameter begins to lessen.

Opposite the tapered portion of the root of the spiral 13 is a guide section comprising upper and lower guide rails 98 and 99 respectively, the inner edges of which are curved to guide the cans in the terminal end of the spiral and onto the conveyor 27 after they are released from the end of the spiral. Preferably these rails are formed as a unitary section, although this is not necessary and said section is provided with an extension 100 which is reversely curved and merges into straight parallel guide rails 101 on the portion 12 of the associated machine.

It should be noted that the inner or operative edge of the guide rail 85 of the hinged section stops short of the pivoted end forming an offset or recess 102 at the hinge sleeve 86, and that the lower rail 88 of the adjacent section of the guide is formed with a nose or extension 103 which projects into said recess. By this arrangement there is never a sufficient break in the continuity of

the guide rails to have any appreciable effect upon the rapidly moving cans. To this end also, the upper guide rail 87 ends a considerable distance from the hinge, and an adjustable supplementary rail section 104 is secured to the adjacent end of the rail 98, and extends beneath the end of the rail 87, thereby bridging the gap between them.

As the cans are delivered from the end of the spiral 13 to the conveyor chain 27, upwardly extending fingers 105 on said conveyor engage behind the cans and move them to the capper. These fingers are arranged alternately on opposite edges of the chain conveyor 27 and are spaced longitudinally thereon to synchronize the feeding of the can in the single row formed by the machine, to the particular type of capper or other machine to which they are to be delivered.

It is believed that from the foregoing description, the invention forming the subject matter of this application and the construction and operation of the specific embodiment thereof as illustrated in the drawings, will be clear. As the invention is adaptable to a variety of uses, and as various minor changes may be made in the specific applications and construction of the device without departing from the invention, it is to be understood that the specification and claims are to be read and construed with this in view.

I claim:

1. In a dual timing machine of the character described, a timing spiral, means for rotating the spiral, conveyors adapted to deliver articles from two sources and in the general direction of the length of the spiral into operative engagement with said spiral along opposite sides thereof, and a center conveyor for removing the articles from the machine substantially along the line of the axis of the timing spiral, all of said conveyors being disposed to operate in the same direction and approximately the same plane and said spiral being adapted to deliver the articles to the center conveyor one at a time and from alternate sides of the spiral.

2. In a dual timing machine of the character described, a timing spiral, means for rotating the spiral, means for delivering lines of cans from two sources and in the general direction of the length of the spiral into operative engagement with said spiral along opposite sides thereof and to move said cans along said spiral with the forward face of each can constantly pressed into engagement with the convolution of the spiral in advance of the can, and a center conveyor at the end of the spiral for receiving the cans alternately from opposite sides of said spiral and feed them away substantially along the line of the axis of the spiral.

3. In a dual timing machine, a substantially horizontal timing spiral, means for rotating the spiral, feed conveyors upon opposite sides of said spiral and parallel therewith, means for delivering cans to said conveyors from separate sources and in the general direction of the length of said spiral and to engage at both sides of said spiral, means for driving said conveyors at a greater speed than the forward movement of the convolutions of the spiral, center conveyor means at the delivery end of the spiral for receiving the cans and delivering the same to another station substantially along the line of the axis of the timing spiral, all of said conveyors being disposed to operate in the same direction and approximately the same plane, the convolutions of the spiral being

such as to first retard the forward movement of the cans and then permit acceleration of the same whereby the can will be delivered to said receiving means alternately from opposite sides of said spiral and at substantially the speed of said receiving means.

4. In a dual timing machine, a timing spiral, means for rotating the same, conveyors upon opposite sides of and parallel with said spiral, means for driving said conveyors, means for delivering cans from separate sources to said conveyors respectively and against opposite sides of said spiral, a center conveyor at the end of the spiral to receive the cans and deliver the same to another station substantially along the line of the axis of the timing spiral, and guides for maintaining the cans in operative engagement with the spiral as they are moved along the same and for guiding the cans onto the center conveyor in a single line as they are delivered alternately from opposite sides of the spiral, all of said conveyors being disposed to operate in the same direction and approximately the same plane.

5. In a dual timing machine, a timing spiral, means for rotating the same, conveyors upon opposite sides of said spiral and parallel therewith, means for delivering rows of cans to said conveyors from separate sources respectively, means for maintaining the cans in engagement with the root of the spiral as they move along the same, a conveyor at the end of the spiral for receiving the cans and delivering the same to the next station, the root diameter of the spiral being uniform for a portion of the length of the spiral and then decreasing to a minus diameter at the delivery end whereby the cans as delivered from the end of the spiral to the last said conveyor will overlap the axis of the spiral.

6. In a dual timing machine, a timing spiral, means for rotating the same, conveyors upon opposite sides of said spiral and parallel therewith, means for delivering rows of cans to said conveyors from separate sources respectively, means for maintaining the cans in engagement with the root of the spiral as they move along the same, a conveyor at the end of the spiral for receiving the cans and delivering the same to the next station, the convolutions of the spiral being such as to initially retard the forward movement of the cans on the conveyors and then to permit acceleration thereof, and the root diameter of the spiral being uniform for a portion of the length of the spiral and then decreasing to a minus diameter at the delivery end whereby the cans as delivered from the end of the spiral to the last said conveyor will overlap the axis of the spiral.

7. In a dual timing machine, a timing spiral, means for rotating the same, conveyors upon opposite sides of said spiral and parallel therewith, means for delivering rows of cans to said conveyors from separate sources respectively, a conveyor at the end of the spiral for receiving the cans and delivering the same toward the next station substantially along the line of the axis of the timing spiral, the root diameter of the spiral being uniform for a portion of the length of the spiral and then decreasing to a minus diameter at the delivery end whereby the cans as delivered from the end of the spiral to the last said conveyor will overlap the axis of the spiral, and guide means extending along each side of the timing spiral and confining travel of the cans so as to maintain contact of the cans with said spiral.

8. In a dual timing machine of the character described, a timing spiral, means for rotating the spiral, conveyors adapted to deliver articles from two sources and in the general direction of the length of the spiral into operative engagement with said spiral along opposite sides thereof, a center conveyor for removing the articles from the machine substantially along the line of the axis of the timing spiral, all of said conveyors being disposed to operate in the same direction and approximately the same plane and said spiral being adapted to deliver the articles to the center conveyor one at a time and from alternate sides of the spiral, and means rotatably supporting the spiral at its receiving end only thereby to leave its delivery end free to deposit cans centrally onto said center conveyor, said spiral having a reduced root diameter at its delivery end to facilitate delivery of cans onto said center conveyor.

9. In a dual timing machine, a substantially horizontal timing spiral, means for rotating the spiral, feed conveyors upon opposite sides of said spiral and parallel therewith, means for delivering cans to said conveyors from separate sources and in the general direction of the length of said spiral and to engage at both sides of said spiral, means for driving said conveyors at a greater speed than the forward movement of the convolutions of the spiral, center conveyor means at the delivery end of the spiral for receiving the

20

30

5 cans and delivering the same to another station substantially along the line of the axis of the timing spiral, all of said conveyors being disposed to operate in the same direction and approximately the same plane, the convolutions of the spiral being such as to first retard the forward movement of the cans and then permit acceleration of the same whereby the can will be delivered to said receiving means alternately from opposite sides of said spiral and at substantially the speed of said receiving means, and there being included means rotatably supporting the spiral at its receiving end only thereby to leave its delivery end free to deposit cans centrally onto said center conveyor, said spiral having a reduced root diameter at its delivery end to facilitate delivery of cans onto said center conveyor.

ROBERT M. MCPHERSON.
